UNITED STATES PATENT OFFICE.

EUGENE R. ALDERMAN, OF HOLYOKE, MASSACHUSETTS.

DOFFING MECHANISM.

Application filed December 14, 1922. Serial No. 606,904.

To all whom it may concern:

Be it known that I, EUGENE R. ALDERMAN, citizen of the United States, residing at Holyoke, in the county of Hampden and 5 State of Massachusetts, have invented new and useful Improvements in Doffing Mechanism, of which the following is a specification.

The present invention relates to doffing 10 mechanism for spinning machines and the like and more particularly to improvements in doffing mechanism of the general character disclosed in United States Letters Patent No. 1,419,192, granted June 13, 1922, to 15 the present applicant.

The patented doffing mechanism above referred to is especially adapted for use in connection with cap spinning machines. In 20 said mechanism a plurality of bobbin-holding pockets are arranged side-by-side in a horizontal row in front of the spindles of the spinning machine. There are two bobbin holding pockets for each spindle, one of 25 said pockets being normally empty and adapted to receive a full bobbin that is to be removed from the spindle, and the other pocket carrying an empty bobbin which is to be placed upon the spindle after the removal of the full bobbin therefrom. The 30 bobbin-receiving and bobbin-delivering pockets are arranged alternately upon a horizontal supporting bar which is slidable longitudinally to bring the receiving and delivering pockets successively into positions opposite the respective spindles. The 35 supporting bar is also movable transversely in a horizontal plane to move the series of pockets toward and from the row of spindles, and in a vertical plane to raise and 40 lower the series of pockets. At the start of the doffing operation, the bobbin-receiving pockets are located directly in front of the respective spindles. After the caps have 45 been removed from the full bobbins on said spindles, the bar which supports the bobbin-holding pockets is advanced laterally toward the spindles to cause the bobbin-receiving pockets to embrace the full bobbins and then 50 said bar is raised to lift said bobbins off from their spindles. The pocket-supporting bar is next shifted longitudinally through a distance equal to the space between the 55 pockets to move the full bobbins into positions midway between the spindles and at

the same time to locate a set of empty bobbins over and in alignment with the spindles. Thereafter said bar is lowered to load the empty bobbins upon the spindles and then moved horizontally to retract the pockets from the spindles, leaving the empty 60 bobbins on the spindles and thus completing the doffing operation.

The above described doffing operation can be carried out successfully by the mechanism of the patent referred to in all cases 65 where the diameter of the full bobbins is appreciably less than half the distance between the spindles, this being the condition in a large majority of spinning mills. Certain mills, however, employ bobbins the diameters of which, either before or after the 70 yarn has been wound thereon, are substantially the same as or greater than half the distance between the spindles. In such cases it is obvious that two bobbin-holding pockets which are large enough to receive the 75 large bobbins cannot be arranged side-by-side within a space equal to the distance between two spindles, and consequently a series of such pockets cannot be arranged with 80 alternate pockets opposite successive spindles.

One object of the present invention is to provide certain improvements in doffing mechanisms of the type disclosed in said 85 Patent No. 1,419,192, for the purpose of adapting such mechanism for use in connection with spinning machines employing bobbins which are too large to be operated upon by said patented doffing mechanism.

Another object of the invention is to provide certain improvements in doffing mechanisms for spinning machines tending to effect substantial economy of aisle space in the mills where the machines are installed.

With the above and further objects in view, as will hereinafter appear, the present invention consists in the features of construction and in the combinations and arrangements of parts hereinafter described 100 and claimed, the advantages of which will be obvious to those skilled in the art.

The invention will be explained with reference to the accompanying drawing showing what is at present considered to be the 105 preferred form of the invention and in which:

Fig. 1 is a top plan view of a portion of

the improved doffing mechanism showing its relation to the spindles of a spinning machine when the doffing mechanism is inactive.

5 Fig. 2 is a front elevational view of the doffing mechanism;

Fig. 3 is a view, partially in side elevation and partially in section, of the mechanism shown in Fig. 2, the section being 10 taken along the line 3—3 of said figure;

Fig. 4 is a detail sectional view of a spring 15 detent device employed in the doffing mechanism;

Fig. 5 is a detail sectional view taken on 20 the line 5—5 of Fig. 2; and

Figs. 6 and 7 are conventional plan views 25 illustrating the movements of the bobbin holding pockets.

The drawings show only so much of a 30 doffing mechanism as is necessary for a clear understanding of the novel features of the present invention, reference being had to the Patent No. 1,419,192, hereinbefore mentioned, for a more detailed disclosure of the 35 construction and mode of operation of certain parts of the mechanism, as well as the cooperation therewith of the spindles of the spinning machine. Referring to the drawings of this application, the spindles of a 40 spinning machine or the like are indicated at 8 in Fig. 1, and the bobbin-receiving and bobbin-delivering pockets of the doffing mechanism are indicated at 10 and 12, respectively. The pockets 10 and 12 are all 45 of the same construction, comprising cylindrical sockets, vertically disposed to support the bobbins, the pockets having portions of their side and bottom walls cut away to provide the slots 14 and notches 16 for the reception of the spindles 8 whereby the 50 pockets are adapted to be brought into positions of axial alinement with the spindles by lateral movements of the pockets. The pockets 10 and 12 are made large enough to 55 receive bobbins which are somewhat greater in diameter than half the distance between the spindles 8.

It is obvious that the pockets 10 and 12 are too large to permit the delivering 55 pockets to be arranged between the receiving pockets when the latter are spaced apart the same as the spindles 8. Therefore it is impossible to perform the doffing operation by the use of receiving and delivering pockets which are disposed in alternate side-by-side relation. In order, however, that the doffing operation may be carried out when bobbins of the large sizes above referred to are employed, the present invention 60 contemplates the arrangement of the bobbin pockets in pairs, each pair consisting of a receiving pocket and a delivering pocket; and the mounting of said pairs of pockets upon separate turrets, the latter being 65 rotatable about vertical axes arranged in

a row and spaced apart the same as the spindles 8, and the receiving and delivering pockets being arranged 180° apart upon the turrets and disposed with their spindle-receiving slots 14 facing outward.

70

Thus, in accordance with the present invention, a plurality of rotatable turrets 18 are provided and these turrets are mounted upon a horizontal bar 20 for rotation in the same horizontal plane. Each turret 18 supports a bobbin-receiving and a bobbin-delivering pocket 12, said pockets being arranged at diametrically opposite sides of the rotational axis of the turret and having its cut-away side outwardly disposed, as clearly 80 illustrated in Fig. 1. The bar 20 is supported with provision for lateral movement both horizontally and vertically as will be hereinafter explained. With the above arrangement it will be evident that the bobbin-receiving pockets 10 are adapted to be simultaneously moved into positions of axial alinement with the spindles 8 by a lateral movement of the supporting bar 20 in the 85 direction of the arrow 22.

90

It is also evident that after the bar 20 has been moved laterally as just described, each of the turrets 18 may be brought into positions of axial alinement with the spindles 8 by rotating each of the turrets 18 through a 95 half turn. In the illustrated embodiment of the invention, however, the turrets 18 cannot be thus rotated simultaneously without interference between the bobbin-holding pockets of adjacent turrets. Accordingly 100 the present invention further contemplates the provision of means for rotating first the alternate turrets of the series through a half revolution and subsequently rotating the remaining turrets similarly.

105

The turrets 18 are rigidly secured by means of screws 24 to the upper ends of vertical rockshafts 28 which are journaled in bearings in the horizontal bar 20. The shafts 28 extend below the bar 20 to receive bevel pinions 30 the hubs of which are rigidly secured to the rockshafts and serve to retain the latter in their bearings. The pinions 30 are severally engaged by multi-lated bevel pinions 32 which are fixed upon a horizontal shaft 34. The shaft 34 is journaled in brackets 36 that support the bar 20. At one side of the mechanism a hand-wheel 38 is secured to the shaft 34 to enable the shaft to be conveniently turned. The teeth extend through 180° on the bevel pinions 32 and said pinions are so positioned radially upon the shaft 34 that the toothed portions of adjacent pinions 32 are disposed at diametrically opposite sides of the shaft 34. With this construction only alternate pinions 30 and consequently alternate turrets 10 can be moved simultaneously by turning the shaft 34. After one set of alternate turrets such as those indicated at A in 110

115

120

125

130

Fig. 1 have been turned each through a half turn by means of the respective mutilated pinions 32, continued turning of the shaft 34 moves said pinions out of mesh with the pinions 30 which they engaged so that the associated turrets A are permitted to remain stationary. The remaining pinions 32 however, which are associated with the other set of turrets (represented by the turret B in Fig. 1) then become operative by intermeshing with their respective pinions 30 to turn the turrets B through a half a turn.

Figs. 6 and 7 illustrate the turning of the turrets in two stages as above explained. In Fig. 6 the turrets of the series A are being turned while the turrets of the series B, which alternate with the turrets A, remain stationary. In Fig. 7 the turrets A remain stationary while the turrets of the series B are being turned. It will be clear from an examination of these two figures that no interference between bobbin-holding pockets of adjacent turrets will result from the carrying out of this method of turning the turrets.

In order that the turrets 18 shall be retained in the positions in which they are left when the respective mutilated pinions 32 are moved out of mesh with the cooperating pinions 30, each turret carries a spring-pressed detent 40, (Fig. 4). As shown, the detent 40 comprises a plunger having a shouldered portion 42 which normally seats against the base of a socket 44 in the turret 18 and a conical lower extremity beyond said shouldered portion 42 which extends through an aperture in the base of said socket and is adapted to engage within a notch 46 in the bar 20. The upper end of the detent plunger 40 extends through and is guided by a cap 48 which is threaded into the upper end of the socket 44. A spring 50 is coiled around the detent plunger between the cap 48 and the shouldered portion 42 and presses the detent toward the bar 20. The notches 46 are so located in the bar 20 that the detents 40 will snap into said notches when the turrets are positioned as shown in Figs. 1 and 2. The conical ends of the detents are so designed that the detents will readily ride out of the notches 46 when the turning of the shaft 34 brings the mutilated pinions 32 into mesh with the respective pinions 30.

In order that the row of turrets 18 may be moved laterally toward and from the spindles 8, the brackets 36 are mounted to slide in horizontal guideways or dovetail grooves 54 in supporting blocks 56 and said brackets are adapted to be shifted in unison in said guideways by means of a series of shift arms 58, that are fast upon a horizontal rockshaft 60. As shown in Fig. 2, a pair of arms 58 are provided for each bracket 36, the arms being arranged at opposite sides of the supporting blocks 56 and having their free ends longitudinally slotted to receive pins 62 that project from opposite sides of the brackets 36 and extend through horizontally elongated slots 64 (Fig. 3) in the supporting blocks 56. The rockshaft 60 is journaled in the several supporting blocks 56 and at one side of the machine has secured thereto a hand wheel 66 for use in turning the shaft. The bar 20, upon which the row of turrets 18 is mounted, is adapted to be raised and lowered by means of rack and pinion mechanism including a plurality of vertical rack bars 68 (Figs. 2 and 3) which support the blocks 56. The rack bars 68 are adapted to be actuated in unison by means of suitable pinions which are mounted upon a single operating shaft, the latter being provided with a suitable hand-wheel by which it may be turned conveniently. The pinions, shaft and hand wheel last mentioned are not shown in the drawings but they may be the same in construction and mode of operation as the corresponding mechanism of applicant's hereinbefore mentioned patent.

In performing the doffing operation with mechanism embodying the present invention, the same general operations take place as described in said patent, with the exception that with the present mechanism the removal of the bobbin-receiving pockets from axial alinement with the spindles and the placing of the bobbin-delivering pockets in the positions initially occupied by the receiving pockets is effected by imparting a half rotation to the turrets 18 instead of by sliding the entire row of bobbin-holding pockets longitudinally as in the patented mechanism. The manner in which the turrets of the present mechanism are rotated will appear with sufficient clearness from the foregoing description taken in connection with the conventional illustration in Figs. 6 and 7, and reference may be had to said patent if desired, for a complete understanding of the other steps in the doffing operation.

While in the present mechanism the row of bobbin-holding pockets is movable laterally toward and from the spindles of the spinning machine for the purpose of placing the bobbin-receiving pockets in axial alinement with the spindles and later for retracting the bobbin-delivering pockets from axial alinement with said spindles, as in said patented mechanism, the means employed in the present mechanism for effecting such movement is an improvement of that employed for the same purpose in said patent. This improved means, which includes the arms 58 and the rock shaft 60, operates fully as well as the rack and pinion devices employed in the patented mecha-

115
120

130

nism and possesses the important advantage of having no parts which project in front of the machine to obstruct the aisle space.

Having thus described the invention what is claimed is:—

1. The combination with a spinning machine or the like employing bobbins having a diameter substantially the same as or greater than one-half the distance between the bobbin spindles, of doffing mechanism for said machine comprising a plurality of horizontally rotatable turrets arranged in a row with one turret located in front of each spindle, a bobbin-receiving pocket on each turret normally positioned in front of the bobbin on the respective spindle, a bobbin-delivering pocket on each turret at the opposite side of the rotational axis from the receiving pocket, means for simultaneously advancing the row of turrets to bring the receiving pockets into axial alinement with the bobbins on the spindles and for thereafter retracting the row of turrets to their initial positions, and means for rotating the turrets to reverse the positions of the receiving and delivering pockets before the row of turrets is retracted. 70
2. The combination with a spinning machine or the like employing bobbins having a diameter substantially the same as or greater than one-half the distance between the bobbin spindles, of doffing mechanism for said machine comprising a plurality of horizontally rotatable turrets arranged in a row with one turret located in front of each spindle, a bobbin-receiving pocket on each turret normally positioned in front of the bobbin on the respective spindle, a bobbin-delivering pocket on each turret at the opposite side of the rotational axis from the receiving pocket, a manually rotatable shaft operative connections including mutilated gears between said shaft and said turrets constructed and arranged to simultaneously rotate alternate turrets to reverse the positions of the receiving and delivering pockets and for thereafter rotating the remainder of said turrets in the same manner, means for retaining the turrets in the positions into which they are turned by said operative connections, and means for simultaneously moving the row of turrets towards the spindles to locate the bobbin-receiving pockets in axial alinement with the bobbins before the turrets have been rotated and for retracting the row of turrets from the spindles after the turrets have been rotated. 75
3. The combination with a spinning machine or the like employing bobbins having a diameter substantially the same as or greater than one-half the distance between the bobbin spindles, of doffing mechanism for said machine comprising a plurality of horizontally rotatable turrets arranged in a row with one turret located in front of each spindle, a bobbin-receiving pocket on each turret normally positioned in front of the bobbin on the respective spindle, a bobbin-delivering pocket on each turret at the opposite side of the rotational axis from the receiving pocket, a carriage upon which said turrets are supported, guideways in which said carriage is mounted, a rockshaft, operative connections between said rockshaft and said carriage for sliding the latter to advance the row of turrets to bring the receiving pockets into axial alinement with the bobbins on the spindles and for thereafter retracting the row of turrets to their initial positions, and 80
4. The combination with a spinning machine or the like employing bobbins having a diameter substantially the same as or greater than one-half the distance between the bobbin spindles, of doffing mechanism for said machine comprising a plurality of horizontally rotatable turrets arranged in a row with one turret located in front of each spindle, a bobbin-receiving pocket on each turret normally positioned in front of the bobbin on the respective spindle, a bobbin-delivering pocket on each turret at the opposite side of the rotational axis from the receiving pocket, a manually rotatable shaft operative connections including mutilated gears between said shaft and said turrets constructed and arranged to simultaneously rotate alternate turrets to reverse the positions of the receiving and delivering pockets and for thereafter rotating the remainder of said turrets in the same manner, means for retaining the turrets in the positions into which they are turned by said operative connections, and means for simultaneously moving the row of turrets towards the spindles to locate the bobbin-receiving pockets in axial alinement with the bobbins before the turrets have been rotated and for retracting the row of turrets from the spindles after the turrets have been rotated. 85
5. The combination with a spinning machine or the like employing bobbins having a diameter substantially the same as or greater than one-half the distance between the bobbin spindles, of doffing mechanism for said machine comprising a plurality of horizontally rotatable turrets arranged in a row with one turret located in front of each spindle, a bobbin-receiving pocket on each turret normally positioned in front of the bobbin on the respective spindle, a bobbin-delivering pocket on each turret at the opposite side of the rotational axis from the receiving pocket, a carriage upon which said turrets are supported, guideways in which said carriage is mounted, a rockshaft, operative connections between said rockshaft and said carriage for sliding the latter to advance the row of turrets to bring the receiving pockets into axial alinement with the bobbins on the spindles and for thereafter retracting the row of turrets to their initial positions, and 90

means on said carriage for rotating the turrets to reverse the positions of the receiving and delivering pockets before the row of turrets is retracted.

- 5 6. The combination with a spinning machine or the like employing bobbins having a diameter substantially the same as or greater than one-half the distance between the bobbin spindles, of doffing mechanism for said machine comprising a plurality of horizontally rotatable turrets arranged in a row with one turret located in front of each spindle, a bobbin-receiving pocket on each turret normally positioned in front of the 10 bobbin on the respective spindle, a bobbin-delivering pocket on each turret at the opposite side of the rotational axis from the receiving pocket, a carriage upon which said turrets are supported, guideways in which 15 said carriage is mounted, a manually operable rock shaft beneath said carriage, arms fixed on said rockshaft, pin and slot connections between said arms and said carriage whereby the latter may be shifted in said 20 guideways by actuation of said rockshaft, and means on said carriage for turning said turrets to reverse the positions of the bobbin-receiving and bobbin-delivering pockets.
7. The combination with a spinning machine or the like, of doffing mechanism therefore comprising a plurality of bobbin-receiving pockets arranged in a row parallel to the row of spindles in the spinning machine, a plurality of bobbin-delivering pockets arranged in a row behind said receiving pockets, means for simultaneously moving said rows of pockets toward said spindles to bring the receiving pockets into axial alignment with said spindles and for simultaneously retracting said pockets from said spindles, and means for reversing the positions of said receiving and said delivering pockets after the receiving pockets have been axially alined with the spindles.

- 45 8. The combination with a spinning ma-

chine or the like, of doffing mechanism therefore comprising a plurality of bobbin-receiving pockets arranged in a row parallel to the row of spindles in the spinning machine, a plurality of bobbin-delivering pockets arranged in a row behind and parallel to said receiving pockets, the delivering pockets being severally arranged opposite the receiving pockets, rotatable parts for each opposed pair of receiving and delivering pockets, means for simultaneously moving said rows of pockets toward said spindles to bring the receiving pockets in axial alinement with said spindles and for simultaneously retracting said pockets from said spindles and means for turning said rotatable parts to reverse the positions of said receiving and said delivering pockets after the receiving pockets have been axially alined with the spindles.

9. The combination with a spinning machine or the like employing bobbins having a diameter substantially the same as or greater than one-half the distance between the bobbin spindles, of doffing mechanism for said machine comprising a plurality of bobbin-receiving pockets arranged in a row parallel to the row of spindles in the spinning machine, a bobbin-delivering pocket adjacent each receiving pocket, means for simultaneously advancing said pockets toward the row of spindles to bring the receiving pockets into axial alinement with said spindles and for subsequently retracting both the receiving and delivering pockets simultaneously from said row of spindles, and means adapted to be operated before said retraction for shifting said receiving pockets out of axial alinement with the spindles and for shifting said delivering pockets into axial alinement with the spindles.

In testimony whereof I have affixed my signature.

EUGENE R. ALDERMAN.
